UNITED STATES PATENT OFFICE.

JAMES E. ROBINSON, OF CHICAGO, ILLINOIS.

RADIATOR-JACKET.

1,136,440.

Specification of Letters Patent. Patented Apr. 20, 1915.

Application filed December 16, 1913. Serial No. 806,983.

To all whom it may concern:

Be it known that I, JAMES E. ROBINSON, a citizen of the United States, residing at Chicago, in the county of Cook and State 5 of Illinois, have invented certain new and useful Improvements in Radiator-Jackets, of which the following is a specification.

This invention relates to improvements in heat insulating devices for use in connection 10 with automobile radiators.

It is a well known fact that an internal combustion engine operates at its highest efficiency when the cooling water flowing through the cylinder jacket is at approximately 15 boiling temperature. If the water in the cooling system attains the temperature of boiling, or above, the supply is rapidly dissipated by evaporation, and as the supply is necessarily limited in automobile 20 practice to a comparatively small quantity, usually three to five gallons, when this has boiled away the engine will reach a dangerously high temperature, burning out the lubricant and permitting the pistons to 25 expand and seize the walls of the cylinders. On the other hand, it is not desirable to have the temperature of the cooling water drop below a point in the neighborhood of 30 175 degrees Fahrenheit, since the efficiency of the engine will be materially lowered. A cool engine results in incomplete combustion of the charge and in the wasting of heat energy through radiation which should have been converted into useful work. For 35 the above reasons the cooling systems on automobiles are designed by the makers to maintain the temperature of the cooling water at somewhat less than 212 degrees Fahrenheit, under normal working conditions. It is common practice to make the 40 radiator cooling surfaces of sufficient area to keep the temperature of the water somewhat lower than the most efficient point, so as to insure against too rapid evaporation.

45 This is the very natural tendency of design, since to permit the water to attain a relatively high temperature, even though this might be the most efficient, might, through carelessness or accident, result in damage to the engine, whereas if the design is such as to normally keep the water at a point considerably less than the most efficient point the likelihood of actual damage is lessened though there is a material loss in efficiency 50 and power under normal conditions. The average temperature at which most of motor

vehicles are operated is, of course, well above the freezing point, and it is for such an average temperature that the cooling system of a car is designed. When, however, 60 the engine is operated at a comparatively low temperature, say for example freezing, 32 degrees Fahrenheit, or below, the heat generated by the combustion within the engine will be sufficient to materially warm 65 the water or "non-freezing solution" to a temperature above freezing, but is insufficient to heat it to a temperature even approaching the boiling point, and when the engine is not running the water is liable to 70 be frozen.

One of the objects of my invention is to provide a device for jacketing the radiator of a motor car in cold weather so as to prevent too great radiation of heat and insure 75 that the cooling fluid may be maintained at a temperature which will be nearer that desired for most efficient working than would otherwise be the case.

Another object of my invention is to provide a device of this nature which can be readily attached to and taken from radiators of different forms with minimum alteration.

Another object of my invention is to 85 provide a radiator jacket of pleasing appearance such as will enhance rather than detract from the appearance of a car.

Other objects will be evident from the following specification and claim.

Figure 1 is a front elevation showing my improved radiator jacket attached to the radiator of a motor car. Fig. 2 is a side elevation of the radiator jacket with a fragmentary vertical sectional view of the 95 engine hood and dash board of a car. Fig. 3 is a fragmentary vertical transverse sectional view on the line 3—3 of Fig. 1. Fig. 4 is a fragmentary plan view looking down upon the top of the radiator. Fig. 5 is a 100 fragmentary horizontal sectional view on the line 5—5 of Fig. 1. Fig. 6 is a fragmentary vertical transverse sectional view on the line 6—6 of Fig. 1. Fig. 7 is a fragmentary perspective view showing the shutter controlling mechanism, and Fig. 8 is a fragmentary vertical transverse sectional view on the line 8—8 of Fig. 1.

In the drawings the numeral 1 indicates the outer shell or casing member of a radiator, such as is commonly used in automobile practice for storing and cooling a sup-

ply of circulating water. Such radiators are usually of a generally polygonal outline and of uniform thickness. The rear face communicates with the interior of the hood which incloses the engine. The radiator is carried upon a transverse bar 3, the ends of which are secured to the longitudinal channel members of the automobile frame, and the starting crank is shown at 4 as extending through the lower portion of the radiator.

A flat plate or sheet of suitable material 5, the edges of which are cut to conform to the outlines of the radiator, is secured to the front face thereof by means of a number of bolts, or screws 6 which extend through the cellular openings in the radiator. The outer edges of the sheet 5 are turned under as at 7 and serve to clamp and hold in proper position a sheet of heat-insulating material 8. This sheet 8 may be of asbestos, or similar heat insulating material, and is of sufficient thickness to prevent the transmission of any appreciable amount of heat therethrough under normal conditions.

Two metallic strips 9 and 10, of width approximately equal to the depth or thickness of the radiator, extend from a point near the radiator filler cap 11 down over the sides to points adjacent the cross members 3. The edges of these strips are curled or bent under as at 12 and 12' to retain a strip of heat insulating material 13 as in the case of the front cover. For the purpose of holding the rear edges of the strips 9 and 10 in close contact with the radiator shell I provide a plurality of clips 14 of substantially S shape, one curve of which extends under the inturned edge 12 of the strip and the other curve of which is bent around the rearwardly extending lip 15 of the radiator shell. The front edges of the strips 9 and 10 are held against the shell of the radiator by means of the L shaped clips 16, the longer leg of which is pressed into contact with the face of the radiator, underlying the front plate 5, the shorter leg extending over the upper edge of the radiator and curved backward, as at 17, to engage with the inturned edge 12' of the strip. The engine hood 2 overlies the straight portion of the S shaped clip 14.

From the above it will be obvious that the device may readily be placed on a car by properly outlining the shape of the radiator upon a flat sheet of metal, curling the edges under, as at 7, and bolting the sheet through the openings in the radiator. A suitable number of the L shaped clips 16 are first placed under the edges of the strips 9 and 10 and then over the front edges of the radiator before the front plate 5 is secured in position. The forward edges 12' of the strips 9 and 10 thus hold the bent edges 17 of the clips 16 and the clips 14 are

held by the rear edges 12. By bending the rearward ends of the clips 14 over the lip 15 of the radiator the side strips 9 and 10 are securely fastened and held in close contact with the shell of the radiator.

In practice the front sheet 5 may be made of zinc, tin, aluminum, Norway iron or other suitable material and supplied in sizes sufficiently large to be subsequently cut to shape, to cover the largest radiator. The side strips 9 and 10 may be provided in two or three sizes as the width of motor car radiators vary but little. The strips 9 and 10 are supplied with attached clips and with the edges turned inward to hold the heat insulating strip 13 in place and may be cut off to suitable lengths for radiators of variable sizes. The adaptability of the jacket and the ease with which it may be placed upon any radiator of usual construction is apparent.

In order that the capacity or the efficiency of the replaceable composite jacket, as a heat insulator, may readily be varied to accommodate the device to different atmospheric temperatures I provide an opening near the center of the front plate 5 and secure therein a register, or damper device, for varying the effective area of the opening. The edges of the opening in the sheet 5 are turned under, as at 18, to present a smooth edge and to protect the inner edges of the insulating sheet 8. A rectangular frame 19 with its upper and lower edges 20 projecting outward, perpendicular to the plate, is secured around the edges of the opening formed in the plate 5. A plurality of rectangular shutters 21 rotatable on their longitudinal axes have their ends 22 pivoted in the side members of the frame 19 and by mutual rotation on their axes can be placed either in interlapped relation, as indicated in dotted lines in Fig. 3, thereby effectually closing the opening in the plate 5 and preventing the passage of cooling air therethrough, or in a horizontal position, as indicated in Fig. 6, so as to permit a maximum amount of air to flow through the opening. Short cranks 23, are formed near one end of each shutter bar, each crank being pivoted in the vertical rod 24 which insures the uniform movement of all of the shutters.

The vertical, outward extending walls of the frame 19 are bent inward to form vertical, elongated closures 25 and 26 the first to inclose the shutter cranks 23 and operating rod 24, and the latter to inclose the shutter operating mechanism. A crank arm 27, one end of which is drilled and fitted with a set screw 28 for connection with any one of the rods 22 of the shutters, is provided for operation of the shutters. The swinging arm 29 of the crank is connected to a flexible cable 30 which extends rearward through an opening 31 in the insulat-

ing sheet 8 and front plate 5, and through a space between the cells in the radiator to a convenient point on the dashboard 32 of the car. A second lever 33 is drilled and fitted 5 with a set screw 34, for connection with any one of the rods 22 of the shutters, its free end being connected to a spring 35, the other end of the spring being secured at 36 to a stationary part. The spring 35 resili- 10 ently holds the shutters normally in open position, as shown in full lines in Fig. 3, the crank arm 27 being so positioned on one of the shutter rods 22 as to cause the closure of the shutters on the rearward movement 15 of the arm.

In order that the register may readily be operated and adjusted from the interior of the car I have provided a Z shaped bracket 20 37, one leg of which is screwed to the dashboard 32 and the other leg of which is slotted, as at 38, to receive a T shaped toothed bar 39. The T shaped bar is provided at 25 one side with a series of projecting lugs or teeth 40 and is connected at its base to the cable 30. The coaction of the projecting lugs 40—40 with the slot 38 permits the cable to be adjusted and positioned at any one of a number of points.

It will be apparent from the above that 30 the shutter mechanism adapts the insulating jacket to varying temperature conditions. Thus for example the shutter operating crank 27, with its cable 30, may be positioned at either side of the opening and again the crank 27 may be secured to any 35 one of the shutters thus permitting both a horizontal and a vertical adjustment of po-

sition. As a result the cable may be ex- 40 tended rearward of the hood, through the radiator on a convenient line, where it will not interfere with the engine mechanism and eliminate the necessity of using pulleys or other direction changing devices, the best of which are apt to become de-arranged and cause trouble.

Whereas I have illustrated the preferred embodiment of my invention it is evident 45 that many changes might be made in the design and general construction of the device without departing from the scope of 50 my invention.

Having described my invention, what I claim is:—

In a heat insulating jacket for an automobile radiator, the combination of a plate 55 adapted to be secured to the front of a radiator, and having its edges turned in; a sheet of insulating material secured to the rear face of the said plate by engagement with the inturned edges; strips positioned upon 60 the sides of the radiator and having their edges turned in; strips of heat insulating material secured to the inner faces of the said inturned strips by engagement with the inturned edges, and retaining clips securing 65 the inturned edge of the plate to the forwardly extending inturned edges of the strips.

In testimony whereof I hereunto set my hand in the presence of two witnesses.

JAMES E. ROBINSON.
